UNITED STATES PATENT OFFICE.

ALEXANDER E. METZ, OF TEANECK, NEW JERSEY.

SCAFFOLD BRACKET.

Application filed July 16, 1926. Serial No. 123,001.

This invention relates to new and useful improvements in scaffold brackets and has for its primary object, the provision of a novel and simplified bracket of the above character so constructed that all of the joints thereof are flexible and further, to provide such a bracket that may be easily and quickly folded when not in use and which, when so folded, will occupy a minimum amount of space.

Another object of the present invention is to provide such an improved bracket of the above character including a pair of hanger bars, a pair of scaffold supporting arms pivotally secured to said hanger bars, and a leg for bracing and retaining said supporting arms in a horizontal position together with improved and simplified means for flexibly connecting the adjacent ends of the said hanger bars and bracing leg together.

A further object of the present invention is to provide such an improved bracket of the above character which is simple yet durable in construction, practical and efficient in use, easy and cheap to manufacture and one which can be placed upon the market at a small cost and readily secured in position for use.

Numerous other objects and advantages of the present invention will become more readily apparent during the course of the following description when taken in connection with the accompanying drawings.

In the drawings forming a part of this application and wherein like characters of reference denote corresponding parts throughout the several views:

Figure 1 is a side elevation of an improved scaffold bracket constructed in accordance with the present invention showing the same secured in position for use.

Figure 2 is a front view thereof.

Figure 3 is a detail perspective view of the forward end of the bracing leg.

Figure 4 is a top plan view of Figure 1.

Figure 5 is a sectional view taken on line 5-5 of Figure 2.

Figure 6 is a detail sectional view taken on line 6-6 of Figure 4.

Referring now more in detail to the accompanying drawings, it will be seen that the present improved scaffold bracket embodies in its construction a pair of vertically disposed downwardly converging hanger

bars 10 and 11, each of which is substantially L-shaped in cross section and includes a flat base portion 12 and the right angularly and forwardly directed flange 13.

The upper end portions 14 and 15 of the said hanger bars are directed at an angle to the lower portions thereof and are arranged in spaced substantially parallel relation relative to one another when the bracket is secured in position for use. The base portions 12 of the end portions 14 and 15 are preferably provided with key hole slots 16 whereby the bracket may be easily and quickly secured in position as will be readily understood.

The flanges 13 of the said hanger bars 10 and 11 project downwardly beyond the base portions 12 thereof and are bent laterally and outwardly to provide the terminal ears 17 and 18 which are substantially parallel with one another when the bracket is secured in position and through which is received the transverse pivot pin 19. The pivot pin 19 is loosely inserted through the said ears 17 and 18 so that the hanger bars 10 and 11 may be forced inwardly into close proximity with one another or may be spread apart as desired. The lower ends of the hanger bars are connected by means of a transverse plate 20 pivotally secured to the base portions 12 of said hanger bars as indicated at 21.

The numerals 22 and 23 generally indicate the forwardly converging scaffold supporting arms, each of which is also substantially L-shaped in cross section as shown to advantage in Figure 6 and comprises a top portion 24 provided at its outer longitudinal edge with a depending flange 25. The depending flanges 25 of the supporting arms 22 and 23 extend rearwardly beyond the top portions 24 thereof and are pivotally connected as at 26 to the forwardly directed flanges 13 of the hanger bars 10 and 11 adjacent the upper ends thereof. The forward ends of the supporting arms 22 and 23 are connected by means of a transverse bridge plate 27 pivotally secured as at 28 to the top portions 24 of the said supporting arms.

For the purpose of bracing the scaffold supporting arms 22 and 23 and for retaining them in a horizontal position, there is provided a bracing leg 29 of substantially T-shape in cross section and comprising a top

portion 30 provided intermediate its longitudinal edges with the depending web 31. The web 31 projects beyond the top portion 30 of the bracing leg 29 at the inner 5 end thereof to provide the terminal foot 32 which is positioned between the terminal ears 17 and 18 and also loosely receives the transverse pivot pin 19 therethrough. Passing transversely through the web 31 adjacent 10 the forward end of the bracing leg 29 is a supporting pin 33 upon the opposite ends of which are secured the sleeves 34.

When it is desired to secure the bracket in position, the key hole slots 16 are first 15 engaged over suitable supporting elements such as nails, screws or the like in the well known manner, after which the supporting arms 22 and 23 are raised to a horizontal position and the upper end of the bracing 20 leg 29 is then inserted between the said arms so that the sleeves 34 carried by the transverse pin 33 will engage the under or bottom faces of the top portions 24 of the said supporting arms.

25 When it is desired to fold the bracket, the bracing leg 29 is first swung upwardly and inwardly so that it will be positioned between the hanger bars 10 and 11 and the bridge plate 20 will act as a stop to limit 30 the inward swinging movement of said leg. The supporting arms 22 and 23 are then swung downwardly and inwardly so that the flanges 25 thereof will rest upon the base 35 portions 12 of the hanger bars 10 and 11 outwardly of the flanges 13 thereof.

Due to the fact that the openings in the 40 terminal ears 17 and 18 through which the pivot pin 19 passes are somewhat larger than said pin, there is provided a flexible joint so that the hanger bars 10 and 11 can be forced inwardly into close proximity relative to one another so that the folded bracket will occupy a minimum amount of space and considerable less space than if the 45 hanger bars were not flexibly connected.

From the foregoing, it is believed that the 50 construction and application of the present invention will be readily apparent and it is to be understood that changes in the details of construction may be resorted to without departing from or sacrificing the spirit of the invention so long as such changes fall within the scope of the appended 55 claims.

What is claimed is:

1. A scaffold bracket, comprising a pair of hanger bars of substantially L shaped cross section adapted to be arranged with the outer face of the flange of each in the same plane to position the outer faces of the other flanges in side opposed relation, said bars converging at their lower ends and having the opposed flanges extended at the lower ends beyond the other flanges and further arranged in spaced parallel relation, scaffold supporting arms each pivotally secured at one end to one of said opposed flanges adjacent the upper end thereof, said arms converging at their outer ends, a bridge plate pivotally connecting the converging lower ends of said bars inwardly of the ends of said extended flanges, a bridge plate pivotally connecting the convergent ends of said arms, a brace leg of substantially T shaped cross section pivotally connected at one end between the ends of said extended flanges, a pin member projecting laterally from the web of said brace member upon each side of the same adjacent the other end thereof, and a sleeve 80 surrounding each end of said pin and engaging beneath a supporting arm, the upper end of said brace leg overlying the bridge plate connecting the arms.

2. A scaffold structure of the character 85 described, comprising a hanger element, a pair of forwardly extending and converging scaffold supporting arms each pivotally secured at one end to said hanger element, each of said arms having an inwardly directed flange extending throughout the length of the same, a bridge plate pivotally connecting the convergent forward ends of said arms, a brace leg pivotally secured at one end adjacent the lower portion of said hanger element and projecting upwardly between said arms with the upper end thereof in overlying relation to said bridge plate, a pin member projecting laterally from each side of said brace leg adjacent the upper 90 end thereof and a sleeve surrounding each end of said pin and engaging beneath the flange of an adjacent scaffold supporting arm.

In testimony whereof I affix my signature.

ALEXANDER E. METZ.
